United States Patent Office

Des. 211,051
Patented May 14, 1968

211,051

CHARM

Randall L. Genung, Sheraton Delta Hotel, Apt. 803,
119 S. Claibourne Ave., New Orleans, La. 70112

Filed Aug. 10, 1967, Ser. No. 8,210

Term of patent 14 years

(Cl. D45—17)

The figure is a front elevation of a charm showing my new design.

The rear of the charm is substantially plain and unornamented, and in side elevation the charm is of conventional thickness.

I claim:

The ornamental design for a charm, as shown and described.
